WELL TUBING HANGER

Wilmer G. Wilson and Charles J. O'Rear, Shreveport, La., assignors to Arkansas Fuel Oil Corporation, Shreveport, La., a corporation of Delaware

Application March 4, 1958, Serial No. 719,041

8 Claims. (Cl. 248—56)

This invention relates to oil and gas well equipment, and more particularly to a new and improved pipe hanger for suspending well tubing, drill pipe, or well casing on a down the hole shoulder of an offshore well.

In the drilling of an offshore well, according to presently utilized techniques, it often becomes necessary to cease operations on very short notice due to turbulent waters caused by intense storms such as hurricanes and typhoons. In suspending such operations it would be more economical and save considerable amounts of time if the major portion of the well tubing, drill pipe, or well casing, whichever is then being worked, could be left in the well rather than removed.

Pipe hangers have been proposed and are available for suspending well tubing, drill pipe and the like in conventional operations. Most of them operate on an undesirable gripping principle in which sharply serrated clamps bite into the pipe surface often damaging the same.

The new and improved hanger of the present invention overcomes the undesirable features of prior art apparatus and permits the suspending of the drill stem, well tubing and the like on a down the hole shoulder of an offshore well thereby eliminating several disadvantages of conventional equipment and methods, such as, possible damage caused by the serrated clamps, or the removal of the entire string of pipe, or the imposing of the entire pipe load on the upper and weaker portion of the conductor-support system. The new pipe hanger is composed of few working parts, is capable of supporting great weights of drill stem, is comparatively inexpensive and may be quickly installed and operated. The latter feature of the present invention is of great advantage when drilling operations must be halted on short notice. The improved pipe hanger of the present invention may be installed on well pipe without removing blowout preventors, control valves and associated equipment.

These and other advantages may be obtained with the apparatus of the present invention which in its broadest aspect comprises a plurality of body sections having associated therewith rotatable load bearing wings which are maintained in hinged relationship to the body sections by means of wing support members. On assembly of the hanger on well tubing or drill stem below a string coupling with the wings in a closed position the tubing may be lowered into the well casing or conductor with the hanger passing through the blowout preventor. On passage through the blowout preventor the load bearing wings are then rotated outwardly by means of a wrench at the surface. The tubing is then further lowered to a point where the wings rest on a down the hole shoulder positioned near the earth surface within the conductor or outer casing. By this means the total weight of the tubing or drill string is supported on the down the hole shoulder by reason of the upper edge of the body sections being in contact with the string coupling.

In the drawings:

Figure 1 is a vertical sectional view of the hanger posi-

2

tioned on the tubing in the casing of an offshore well.

Figure 2 is a cross sectional view taken along the line 2—2 of Figure 1.

Figure 3 is a perspective view of the upper portion of 5 the hanger body sections showing the hanger as assembled for use.

Referring now to the drawings, and in particular Figures 1 and 3, numeral 1 designates the well conductor pipe of an offshore well. Conductor 1 normally extends 10 above the surface of the water, and terminates a short distance below the surface of the earth underlying the water. Within conductor 1 a string of well casing 2 is positioned penetrating the earth surface substantially to the drilling zone or to the production zone after 15 drilling has been completed. Casing 2 terminates at its upper end in a down the hole shoulder identified as 3. Shoulder 3 is generally integral with the adjacent portion of well casing indicated by 4 which as shown in the drawing will be of larger diameter than casing 2. The 20 upper portion of casing 2 is cemented to conductor 1. As shown in Figure 1, the down the hole shoulder indicated at 3 is integral with casing 2 and is firmly affixed by welding indicated at 37 to casing 4. While this arrangement is satisfactory, it is preferred that the shoulder 25 3 be fashioned or made an integral part of that portion of the string joining sections 4 and 2.

In the preferred embodiment of this invention as shown in Figure 3, the new and improved pipe hanger generally indicated by numeral 8 comprises three body 30 sections identified as 8a, 8b and 8c. Each body section has a curved inner surface to permit the section to fit snugly against the tubing or drill pipe as indicated by numeral 6. The length and size of the respective body sections will of course vary in accordance with the size 35 and length of pipe to be supported. The upper edge of the respective body sections terminates in a flat surface 36 which will rest against the lower end of a string coupling identified as 7 when the hanger is assembled on the well tubing.

In the lower portion of each body section an adjustable screw 10 is provided to insure a tight fit of the hanger on the pipe or tubing when the hanger is assembled thereon.

Each body section includes wing support members 45 identified as 9a, 9b and 9c. These support members may be fabricated as a part of the body section or fastened thereto by welding or other means. The support members terminate in a slightly enlarged and curved end portion identified as 20 which has a hole identified as 21 therein for the purpose of receiving pin 13 as is more completely described hereafter. The wing supports 9a, 9b and 9c are horizontally positioned on the body sections and vertically aligned with one another so that when the body sections are assembled as shown in Figure 3, the expanded end portions 20 of adjacent wing support members will overlap. To enable the body sections to be assembled in hinged relationship and to insure that the load bearing wings 12 will terminate at a common level, the end portions of one series of wing support members will be placed in stepped relationship 50 to each other so as to permit interlocking with adjacent wing support members of adjacent body sections. This will be more clearly evident by referring to body section 8c, on which are positioned the wing support members identified as 9c and 9c'. This permits wing support member 9a to rest on 9c', and 9c to rest on wing support 55 9b of body section 8b. In a similar manner, the other wing support members of the respective body sections are placed in overlapping relationship. If more or less than three body sections are used, the number 60 and position of the wing support members on adjacent body sections must be adjusted accordingly.

Wing support members are vertically positioned on the respective body sections in such a manner that when the end portions of adjacent support members overlap, sufficient space remains between adjacent support members to permit the curved end portions 27 to load bearing wings 12 to be inserted.

Load bearing wings 12 are equal in number to the body sections and terminate at their upper end in a flat surface 22, and the lower end at flat surface 23. Load bearing wings 12 include curved end portions identified as 27 at fixed space intervals sufficient to span the end portions of adjacent wing support members when the body sections are assembled adjacent to each other. The number of open spaces identified by numeral 25 between the respective end portions 27 of a load bearing wing will vary in accordance with the number of wing support members on the body section and the number of curved end portions 27 of the load bearing wings required to fit the open spaces created by the wing support members. It will be noted that the inner surface 24 of load bearing wings 12 is rounded to permit the rotation of wing 12 after the wing 12 is placed in hinged relationship with the expanded end portions of adjacent wing support members.

The expanded end portions 27 of wings 12 includes a pin receiving hole 29. This hole is of similar size to the holes provided in the expanded end portions 20 of the wing support members on the respective body portions. In addition to the vertical pin receiving hole 29 in wings 12, screws 14 are provided to prevent pin 13 from being withdrawn from the respective expanded end portions once pin 13 is inserted therein. When fixed in position screw 14 permits rotation of load bearing wings 12 when a wrench or other turning means is applied to the upper end of pin 13.

Hinge pin 13 at its upper end terminates in a nut 28 or other configuration adapted to receive extension rods 15. A hole in nut 28 permits insertion of screw 33. This prevents vertical separation of hinge pin 13 from extension rods 15. Pins or keys may be substituted for screws 33 if desired. A short distance below the upper end of hinge pin 13 a flange 34 is provided, adapted to rest on the upper flat surface 22. Hinge pin 13 is fashioned so that it may be inserted in the holes 29 of load bearing wings 12. Pin 13 is of sufficient length to pass through holes 21 and 29 and terminates in the lower extension of the wing 12. Holes are provided in hinge pin 13 at points coincident with the similar holes in load bearing wings 12 for the insertion of screws 14. The structure of hinge pin 13 may be varied if desired. For example, pin 13 may be a square or other similar configuration. This will necessitate a change in hole 29 of wings 12 to a corresponding configuration so that rotation of pin 13 will rotate wings 12.

The nut 28 is a hexagon or other suitable configuration adapted to receive socket 30 of extension rods 15. Flange 34 may be eliminated if hole 29 does not pass through the lower end of load bearing wings 12.

Extension rods 15 extend upwardly from hinge pin 13 and are of sufficient length to enable pin 13 to be rotated from the surface after hanger 8 is wrapped around the tube and passed through the blowout preventor and control valve. The upper end of extension rod 15 terminates in a nut 17 and at their lower end in a socket 30 adapted to receive nut 28 of pin 13. A hole is provided through socket 30 at a position corresponding to the hole provided in nut 28 for screw 33. If desired, slot or key means, together with a corresponding slot or key means in nut 28, may be substituted for socket 30.

If desired, extension rods 15 may be stabilized by positioning a short distance above coupling 7 on the well tubing 6 a guide bracket 16. Bracket 16 may consist of separate body portions held in fixed relationship as by bolts 18. The end portions of bracket 16 indicated by numeral 16a must be of sufficient diameter to permit rods 15 to pass through. In addition, tube guides 19 may be in-

stalled on the lower portion of the respective body sections to center the tubing in the well casing. Guide members 19 insure engagement of the load bearing wings 12 in their open position on the down the hole shoulder 3. Similar to the wing support members, guides 19 may form an integral part of the respective body sections or be permanently fixed thereto by welding or other means.

Preparatory to inserting pipe hanger 8 in well casing 4, a portion of well tubing 6 is raised to the surface. This portion must be of sufficient length to prevent the lower end of tubing 6 from resting on the formation at the bottom of the bore hole when the pipe hanger engages the down the hole shoulder. To position hanger 8 on the tubing, the screws 14 from any hinge pin 13, the pin 13 and the attached load bearing wing 12 are removed. The body sections 8a, 8b or 8c adjacent to the removed pin 13 are rotated outwardly on the remaining hinge pins 13, thus permitting the pipe hanger 8 to be wrapped around the well tubing 6.

The load bearing wing 12 is returned to its position. Pin 13 is inserted in holes 21 and 29, and screws 14 are installed in wing 12 and pin 13. Pin 13 holds wing 12 in hinged relationship to support members 9a, 9b and 9c, thus permitting the rotation of wings 12. The pipe hanger 8 is raised until it rests against the lower end of coupling 7. Hanger 8 is then locked in position by screws 10. Extension rods 15 are installed on nuts 28 and screws 33 fastened.

Extension rods 15 are turned, thereby rotating hinge pins 13 and the load bearing wings 12 fastened thereto in toward the body sections.

The string of tubing with the hanger 8 attached is lowered in the well casing 4 until the hanger 8 passes through the blowout preventors. By means of a wrench applied to the nut 17, the load bearing wings 12 are rotated outwardly from the body sections. Tubing 6 is now lowered until the load bearing wings 12 engage the down the hole shoulder 3. The lower surface 23 of wing 12 rests on the flat portion of down the hole shoulder 3. The weight of well tubing 6 is thus transferred from coupling 7 to hanger 8.

If it is desired to remove hanger 8, the tubing 6 is raised until nut 17 passes through the blowout preventor. A wrench is applied to nut 17 to rotate wings 12 in toward the body sections. Tubing 6 is then raised until hanger 8 reaches the surface. Screws 33 and extension rods 15 are removed. Screws 10 and 14 are removed. Pin 13 and wing 12 are removed and the body sections adjacent to the removed pin are rotated outwardly, thus permitting the removal of hanger 8.

From the foregoing, it is apparent that the present invention provides a novel pipe hanger for securing a string of well tubing in a well casing. The weight of the string of tubing, rather than being supported from the surface as by the top of the conductor, is supported on a down the hole shoulder.

While we have described our invention with a certain degree of particularity, it is, of course, understood that changes in details and combinations and arrangement of operations may be resorted to. If desired, for example, the hanger may be constructed of two body sections or four or more sections, rather than the three sections shown. When so constructed, the necessary modifications to the number, size, and space relationship of the respective wing support members and load bearing wings must also be made. Such changes, of course, would be resorted to without departing from the scope and spirit of this invention, which is to be limited only by the claims appended hereto.

We claim:

1. A pipe hanger adapted to suspend the well tubing on a down the hole shoulder in the casing of an offshore well comprising an elongated body portion attachable to the well tubing, said body portion comprising at least two sections, said sections having an inner surface shaped

to fit the tubing and an outer surface including a plurality of vertically spaced wing support members horizontally extending beyond the body sections and terminating in an expanded end portion, said expanded end portion having a hinge pin receiving hole therein, said wing support members positioned so as to be in overlapping interlocked relationship with other wing support members when the body sections are placed adjacent to each other, a plurality of rotatable load bearing wings held in hinged relationship to the wing support members by hinge pins, said wings terminating in a load bearing lower edge, and said pins terminating at their upper end in means to effect the rotation thereof.

2. A pipe hanger adapted to suspend the well tubing on a down the hole shoulder in the casing of an offshore well comprising an elongated body portion attachable to the well tubing, and adapted to rest against the lower edge of a tubing coupling, said body portion comprising at least two sections, said sections having an inner surface shaped to fit the tubing and an outer surface including a plurality of horizontally extending and vertically spaced wing support members terminating in an expanded end portion, said expanded end portion having a hinge pin receiving hole therein, said wing support members positioned to overlap other wing support members of adjacent body sections, a plurality of rotatable load bearing wings hinged to the wing support members by hinge pins, said wings terminating in a load bearing lower edge and said pin terminating at its upper end in means to effect the rotation thereof.

3. A pipe hanger adapted to suspend the well tubing on a down the hole shoulder in the casing of an offshore well comprising an elongated body portion attachable to the well tubing, said body portion comprising at least two sections, said sections having an inner surface shaped to fit the tubing and an outer surface including a plurality of vertically spaced wing support members horizontally extending beyond the body sections and terminating in an expanded end portion, said expanded end portion having a hinge pin receiving hole therein, said wing support members positioned so as to be in overlapping interlocked relationship with other wing support members when the body sections are placed adjacent to each other, a plurality of rotatable load bearing wings held in hinged relationship to the wing support members by hinge pins, said wings terminating in a load bearing lower edge, and said pin terminating at its upper end in means to effect the rotation thereof, said means comprising extension rods having associated therewith a bracket positioned on the well tubing above said hanger, said bracket designed to maintain the extension rods perpendicular to said hanger.

4. A pipe hanger adapted to suspend the well tubing on a down the hole shoulder in the casing of an offshore well comprising an elongated body portion attachable to the well tubing and having included on its lower end guide members positioned to center the hanger in the tubing, said body portion comprising at least two sections, said sections having an inner surface shaped to fit the tubing, and an outer surface including a plurality of vertically spaced wing support members horizontally extending beyond the body sections and terminating in an expanded end portion, said expanded end portion having a hinge pin receiving hole therein, said wing support members positioned so as to meet in overlapping interlocked relationship with other wing support members when the body sections are placed adjacent to each other, a plurality of rotatable load bearing wings held in hinged relationship to the wing support members by hinge pins, said wings terminating in a load bearing lower edge and said pin terminating at its upper end in means to effect the rotation thereof.

5. A pipe hanger adapted to suspend the well tubing on a down the hole shoulder in the casing of an offshore

well comprising a centrally located elongated body portion attachable to the well tubing, said body portion comprising at least two sections, said sections having their inner surfaces shaped to fit the tubing and an outer surface 5 having attached thereto a plurality of vertically spaced wing support members horizontally extending beyond the body sections and terminating in an expanded end portion, said expanded end portion having a hinge pin hole therein, said wing support members positioned so as to be in overlapped relationship with other wing support members of adjacent body sections, a plurality of rotatable load bearing wings held in hinged relationship to the wing support members by hinge pins, said wings having holes positioned therethrough for insertion of 10 screws and terminating in a load bearing lower edge, said pin comprising a cylindrical column containing holes positioned therethrough corresponding to the holes in the load bearing wings for the insertion of screws of sufficient length to pass through the hinge pin and load 15 bearing wing, and terminating at its upper end in means to effect the rotation thereof.

6. A pipe hanger adapted to suspend the well tubing on a down the hole shoulder in the casing of an offshore well comprising an elongated body portion attachable to the well tubing, said body portion comprising at least two sections, said sections having an inner surface curved to fit the tubing and an outer surface to which are attached a plurality of wing support members horizontally extending beyond the body sections and terminating in 20 an expanded end portion, said expanded end portion having a hinge pin receiving hole therein, said wing support members positioned so as to meet in overlapping interlocked relationship with other wing support members of adjacent body sections, a plurality of rotatable load bearing wings terminating in a load bearing lower edge and adapted to interlock the wing support members of adjacent sections, said wings being held in hinged relationship with the wing support members and movable by a hinge pin and said hinge pin having means attached 25 to its upper end to effect rotation thereof.

7. A pipe hanger adapted to suspend the well tubing on a down the hole shoulder in the casing of an offshore well comprising an elongated body portion attachable to the well tubing, said body portion comprising three sections, said sections having a curved inner surface shaped to fit the tubing and an outer surface to which are attached a plurality of wing support members horizontally extending beyond the body sections and terminating in an expanded end portion, said expanded end portion having a hinge pin receiving hole therein, said wing support members positioned so as to meet in overlapping interlocked relationship with the other wing support members when the body sections are placed adjacent to each other, a plurality of rotatable load bearing wings held in hinged relationship to the wing support members by hinge pins, said wings terminating in a load bearing lower edge and said hinge pin terminating at its upper end in means to effect the rotation thereof.

8. A pipe hanger adapted to suspend well tubing on a down the hole shoulder in the casing of an offshore well comprising an elongated body portion attachable to the well tubing, said body portion comprising at least two sections and having an inner surface adapted to engage said tubing; sets of vertically spaced wing support members extending horizontally beyond the respective body sections adjacent the longitudinal margins thereof, wing support members of each such set being positioned so as to meet in overlapping interlocked relationship with wing support members of an adjacent body section; a plurality of rotatable load bearing wings terminating in load bearing lower surfaces and having projecting portions adapted to interlock with wing support members of adjacent sections; hinge means for se- 70 75

curing said load bearing wings in hinged relationship with said wing support members; and means for rotating said load bearing wings with respect to said wing support members.
